WESTERN ELECTRIC COMPANY, INCORPORATED, A CORPORATION OF NEW YORK.

MODULATING SYSTEM.

Application filed January 15, 1925. Serial No. 2,486.

This invention relates to translating circuits, and more particularly to the circuits of space discharge modulating devices.

An object of the invention is to increase 5 the output of useful energy of a modulator, preferably of the space discharge type.

A feature of the invention is the combination with the modulating device of load or output circuit having an impedance which 10 varies with the wave frequency according to a special mode.

Other objects of the invention and the principle of its operation will be clearly understood from the following detailed description when read in connection with the 15 accompanying drawings, of which

Fig. 1 shows in schematic form a modulating system embodying the invention;

Fig. 2 shows attenuation characteristics 20 relating to the system of Fig. 1; and

Fig. 3 shows impedance characteristics corresponding to the attenuation characteristics of Fig. 2.

The system shown in schematic form in 25 Fig. 1 includes the necessary apparatus for preparing and transmitting a single side band of high frequency waves for the purpose of radio telephone communication by the so-called homodyne method. In accordance with this method, a high frequency carrier wave is modulated by speech waves and from the modulation products one side band corresponding to the speech waves is selected 30 for transmission, the other side band and the carrier wave both being suppressed by suitable selective circuits. At the receiving point, a local generator supplies an auxiliary wave of the proper frequency, usually that 35 of the suppressed carrier, which is impressed along with the received waves upon a demodulator, thereby enabling the transmitted 40 signals to be properly detected.

The advantages accruing from the method are principally an economy of power due to 45 the restriction of the number of waves transmitted, a more efficient use of the frequency spectrum due to the elimination of one side band, and, in the case of radio signaling, a certain degree of secrecy due to the absence 50 of the carrier wave.

As illustrated, the system comprises a balanced space discharge modulator 1, of

the type disclosed in U. S. patent to J. R. Carson, No. 1,343,307, issued June 15, 1920, upon the input terminals of which are impressed 55 speech frequency waves from microphone 2 and a carrier wave from a source 3.

The products of modulation are impressed through a balanced output transformer 4 upon a high-pass wave filter 5, the cut-off 60 frequency of which is so adjusted that only those waves corresponding to the sum of the two input frequencies, that is, the higher frequency side-band waves, are freely transmitted. This filter may be of the well known 65 type disclosed in U. S. patent to G. A. Campbell, No. 1,227,113, issued May 22, 1917, but is preferably a composite filter, having a very great attenuation at frequencies close 70 to the cut-off frequency. Filters of this general type are described by O. J. Zobel, "Theory and Design of Composite Electric Wave Filters", Bell System Technical Journal, Vol. II No. 1, January, 1923. The balanced modulator in accordance with the 75 Carson patent mentioned above delivers to the filter only the side-band modulation products and those amplified waves corresponding to the speech input, the amplified carrier wave being balanced out by the windings of transformer 4. Filter 5 is therefore required to suppress only the speech waves, the lower side-band of the modulation products, and such small fraction of the carrier wave as may result from imperfections 80 of the output transformer balance.

The selected side-band is impressed upon a second space discharge modulator 7 through transformer 6 and is modulated therein with a second carrier wave supplied from source 80 through transformer 9. A band-pass filter 8 selects from the output of modulator 7 one band of side frequencies and transmits them to an amplifier 11, which may be of any well known type, from the output of 85 which waves of amplified energy are delivered to a radiating antenna 12. Filter 10, as illustrated, consists of a single mid-shunt terminated section, but additional sections may be used if desired.

The first step of modulation in modulator 1 produces side-bands of waves which lie in the frequency spectrum close to the carrier wave. The selection of a single side-

band, while at the same time the other is substantially suppressed, requires a sharply discriminating selectivity in the filter 5. In practice, it has been found that such selection cannot be efficiently accomplished if the frequency of the carrier wave is much above 40 kilocycles per second.

The use of a carrier wave of about 30 kilocycles per second frequency provides, as the result of the first step of modulation and selection, a band of waves of frequencies ranging from 30 kilocycles per second up to about 35 kilocycles per second, and these waves when modulated in the second modulator 7 with the second carrier wave produce side-bands which are separated from the carrier wave by a frequency difference of at least 30 kilocycles. The second wave may be of comparatively high frequency, for example 100 kilocycles per second, without imposing upon the filter 10 any severe requirements as to selectivity.

The problem of preparing a single side-band, or a single band of pure modulated waves, involves not only the problem of selection as outlined in the foregoing, but also that of securing the maximum power output from the modulating devices.

A mathematical theory of modulators, having particular reference to simple space discharge modulators of the three-electrode type, is contained in U. S. patent to J. R. Carson, No. 1,448,702, issued March 13, 1923.

The following formulæ are given in the above noted patent for the side frequency current components of the products of the modulation in a space discharge amplifier:—

$$I_{(t_2-t_1)} = M(\mu R_o)^2 \frac{E_1 \cdot E_2}{Z_{f_1} \cdot Z_{f_2} \cdot Z_{(t_2-t_1)}} \quad (1)$$

and

$$I_{(t_2+t_1)} = M(\mu R_o)^2 \frac{E_1 \cdot E_2}{Z_{f_1} \cdot Z_{f_2} \cdot Z_{(t_2+t_1)}} \quad (2)$$

the various factors of which are defined as follows:

E_1 and E_2 are respectively the amplitudes of the carrier wave and the signal wave electromotive forces impressed upon the modulator input terminals, both waves being assumed to be sinusoidal;

Z_{f_1} and Z_{f_2} are the impedances of the modulator output circuit, including the internal resistance of the modulator, corresponding to the frequencies f_1 and f_2 of the carrier wave and the signal wave respectively; $Z_{(t_1+t_2)}$ and $Z_{(t_2-t_1)}$ are the corresponding impedances at the frequencies of the modulation product components, that is, at the upper and lower side frequencies; μ is the amplification factor and R_o is the internal resistance of the modulator. The factor M is a constant the value of which depends upon the rate of variation of the

resistance R_o with the anode potential E_o of the modulator in accordance with the following equation:—

$$M = \frac{1}{2R_o} \cdot \frac{dR_o}{dE_o} \quad (3) \quad 70$$

The power output of the modulator in a given side-band, for example the lower frequency band, is equal to the square of the current component of that frequency multiplied by the resistance of the connected output circuit at that frequency. From equation (1) it is evident that the side-band power output may be expressed by

$$P = K \frac{R_{(t_2-t_1)}}{Z_{f_1}^2 \cdot Z_{f_2}^2 \cdot Z_{(t_2-t_1)}^2} \quad (4)$$

in which P is the power output, and $R_{(t_2-t_1)}$ is the resistance of the connected output circuit at the frequency (f_2-f_1) . The factor K involves the coefficients, μ , R_o , and M , and the voltage E , and is a constant so long as the voltage is constant.

The power output being determined in part by the load resistance, the impedance conditions necessary to produce the maximum power may be determined by computing the partial derivative of the foregoing expression for the side-band power with respect to the load resistance, and equating the result to zero in the usual manner. In this way, the following equation is found which states a condition for maximum power:

$$Z_{t_1} \cdot Z_{t_2} \cdot Z_{(t_2-t_1)} = 2R_{(t_2-t_1)} \left\{ Z_{t_1} Z_{t_2} \frac{\partial Z_{(t_2-t_1)}}{\partial R_{(t_2-t_1)}} + Z_{t_1} Z_{(t_2-t_1)} \frac{\partial Z_{t_2}}{\partial R_{(t_2-t_1)}} + Z_{(t_2-t_1)} Z_{t_2} \frac{\partial Z_{t_1}}{\partial R_{(t_2-t_1)}} \right\} \quad (5) \quad 105$$

To demonstrate the extent by which the power output may be modified by the proportioning of the connected output impedance, the maximum power output in three important cases will be determined.

Case 1. The load impedance is a resistance and the same at all frequencies.

In this case the impedances Z_{t_1} , Z_{t_2} , and $Z_{(t_2-t_1)}$, are each equal to

$$R_o + R_{(t_2-t_1)} \quad (6)$$

that is, to the internal resistance of the modulator plus the constant resistance of the connected output circuit.

Substitution of this value in equation (5) gives the solution

$$R_{(t_2-t_1)} = \frac{1}{5} R_o \quad (7) \quad 125$$

the partial derivatives being all equal to unity.

From equation (4) by means of equations

(6) and (7), the maximum power is found to be

$$P = \frac{K}{R_o^5} \cdot \frac{1}{5} \left(\frac{5}{6}\right)^6 \quad (8)$$

5 *Case 2.* The load impedance is zero to waves of frequency f_1 and is uniformly resistive to waves of the other frequencies.

The impedances are

$$Z_{f_1} = R_o$$

$$Z_{f_2} = Z_{(f_2-f_1)} = R_o + R_{(f_2-f_1)} \quad (9)$$

10 The partial derivative of Z_{f_2} in equation 15 (4) is zero and the other partial derivatives are each unity. The solution of equation (5) obtained when the values of equations (9) are substituted therein is

$$20 R_{(f_2-f_1)} = \frac{1}{3} R_o \quad (10)$$

which corresponds to a maximum power

$$25 P = \frac{K}{R_o^5} \cdot \frac{1}{3} \left(\frac{3}{4}\right)^4 \quad (11)$$

30 *Case 3.* The load impedance is zero to waves of both frequencies f_1 and f_2 and is resistive at the side band frequency.

The impedances are

$$35 Z_{f_1} = Z_{f_2} = R_o \\ Z_{(f_2-f_1)} = R_o + R_{(f_2-f_1)} \quad (12)$$

40 The substitution of the values defined by equations (12) in equation (5) leads to the solution

$$R_{(f_2-f_1)} = R_o \quad (13)$$

45 for which condition the power output as given by equation (4) is

$$P = \frac{K}{R_o^5} \times \frac{1}{4} \cdot (14)$$

50 The maximum powers obtainable in the three cases investigated are in the proportions

$$1 : 1.57 : 3.73$$

55 indicating that a very great increase in side band power may be obtained if the connected output impedance is so designed as to have a characteristic variation with frequency that accords with the requirements stated in connection with the third case.

60 The modulating systems of the present invention embody features whereby this increased power output is obtained.

65 In the system of Fig. 1 the conditions giving rise to the optimum power output from second modulator 7 are obtained by the cooperation of two features. The first is the use of a mid-shunt termination of the band-pass filter 10 in the output circuit of the modulator for the selection of the proper side band and the suppression of the other waves.

The second is the wide separation of the side bands from the second carrier wave, thus being secured as a result of the first stage of modulation.

70 The characteristic curves of filter 10 are shown in Figs. 2 and 3, in the former of which the curve A represents the frequency-attenuation characteristic and in the latter of which the discontinuous curve B₁ B₂ B₃ represents the frequency-impedance characteristic. The transmission limits of the filter are indicated by the frequencies f_a and f_b . Between these limits the impedance is resistive; infinitely great at the limits but falling rapidly to a fairly uniform value 80 throughout the greater part of the range.

85 Outside the limits the impedance is reactive. It is inductive below the lower limit and falls rapidly to a low value as the frequency decreases; above the upper limit it is capacitive and falls rapidly to zero as the frequency increases. By well known methods the filter may be so proportioned that the resistance between the band limits is equal to the modulator internal resistance 90 for a substantial range of frequencies. A possible relationship between the two resistances is illustrated in Fig. 3 by the curved line B₂ representing the filter resistance and the straight line DD¹ representing the modulator resistance. 95

100 Figs. 2 and 3 show also the characteristics of the filter 5, the attenuation characteristic being represented in Fig. 2 by the discontinuous curve G, the discontinuity of which corresponds to the resonance of the anti-resonant circuit 13 in the series terminal branch of the filter, and the impedance characteristic being shown in Fig. 3 by the discontinuous curve H₁ H₂ H₃. The various 105 wave frequencies involved in the production of the final side band are also indicated.

110 In modulator 1 a wave of frequency f_s which may be considered as one component of a complex speech wave modulates a carrier wave from source 3 having a frequency f_c which is preferably equal to or slightly less than the cut-off frequency of filter 5.

115 Amongst the products of modulation is a wave of frequency $f_1 (=f_c + f_s)$, which is transmitted through the filter to the input of modulator 7 in which it is applied to modulate the second carrier f_2 supplied from source 8.

120 As may be seen from Figs. 2 and 3 it is necessary that the second modulation product of frequency $f_2 - f_1$ should fall between the limits f_a and f_b of the band filter 10, in consequence of which f_2 must lie well outside these limits. The relative positions of 125 these waves in the frequency spectrum are clearly indicated in the diagrams.

130 In the load circuit the waves of frequencies f_1 and f_2 encounter practically zero impedance, whereas the side-band wave of fre-

quency $f_2 - f_1$ encounters a resistance practically equal to that of the modulator tube. The conditions are therefore correct to obtain the greatest possible amount of power from the modulator. It should be noted also that the second carrier wave being well outside the transmission range of the filter is strongly attenuated thereby.

The action in the output circuit of modulator 1 is of a similar character but is slightly different in detail. Filter 5 is terminated mid-series instead of mid-shunt in consequence of which the impedance is zero at the cut-off frequency, instead of being infinite as in the case for mid-shunt termination. By setting the frequency of the first carrier wave equal to or slightly lower than the cut-off frequency the desired condition that the load impedance be zero to the carrier wave is attained. If an ordinary Campbell type high-pass filter were used the impedance would, on account of the series capacity, increase towards infinity at low frequency, and the condition of low impedance to the second input wave f_s could be attained only by making the impedance of transformer 4 sufficiently low at speech frequencies. However, the use of the special termination shown in the figure produces an impedance characteristic which falls to zero at very low frequencies and thereby secures the desired condition of zero impedance in the load circuit to both of the input waves.

The use of a balanced type modulator for the first stage of modulation secures by the neutralizing action of windings of the output transformer 4, an output impedance which is effectively zero at the frequency of the carrier wave, and at the same time substantially suppresses the carrier wave. In a modulator of this sort the effect of the load impedance characteristic is therefore principally to supplement the action of the output transformer at the carrier wave frequency and to provide the lowest possible impedance for the waves of speech frequency.

If instead of a balanced modulator as shown, a simple modulator, such as is used for the second step, were employed the filter would still provide the desired impedance characteristic by which the maximum power output is attained. The carrier wave, however, would not be completely suppressed but would be partially transmitted with the side frequencies to the second modulator and would appear in the output of the antenna 12 in conjunction with the final side band. The radiated wave would then no longer consist of pure modulated waves but would be accompanied by a carrier wave component, enabling the signals to be detected by simple detectors. The advantages of single side band transmission are, however, retained, namely an economy of power and the use

of a smaller frequency range for the communication channel.

The system shown in Fig. 1 may be made to operate in accordance with this method by opening switch 14 in the output circuit 70 of one modulator thereby rendering that modulator inoperative.

In each of the modulation systems described a unique maximum power output is obtained by so arranging the connected load 75 circuit that it provides a short circuit or zero impedance path to the amplified waves corresponding to each of the input waves, and that it provides a resistive path for the modulation products, equal in resistance to 80 the modulator space path. By the use of a broad band filter structure the equality of the modulator and the load resistance is maintained over a substantial range of frequencies thereby enabling a band of signal 85 waves to be efficiently transmitted.

The operation of a space discharge modulator in producing the maximum side band power may be described very briefly as follows:—when the amplified currents corresponding to the impressed waves are permitted to attain their maximum intensity in the space discharge path, the maximum side band electromotive force is generated therein, and the maximum side band power 95 output is delivered to a load resistance when that resistance has the same magnitude as the internal resistance of the modulator, or side band generator.

The mode of operation is not peculiar to 100 space discharge modulation but is broadly applicable to modulating systems in general. In the space discharge modulator the feature that causes the generation of the modulation products is the variability of the space 105 path resistance according to the intensity of the impressed forces. In modulators generally, it is the variability of the impedance of some particular element in accordance with the intensity of the waves by 110 which it is traversed that results in the generation of the modulation products, and, in order that the modulation product forces, for example the side-band electromotive force, may be a maximum, it is necessary that the 115 waves traversing the modulating element be permitted to attain their maximum intensity. The subsequent transmission of the side band power is a maximum when the conditions of the familiar generator law are 120 fulfilled.

What is claimed is:

1. A modulating system comprising in combination, a space discharge modulating device having an anode, a cathode and a 125 control electrode, means for impressing simultaneously upon said control electrode a carrier wave and a band of signal waves, whereby there are generated in the space path of said device side bands of waves 130

- having frequencies differing from the carrier wave frequency by the frequencies of the signal waves, and a broad band wave filter connected to said anode and said cathode adapted to transmit selectively one of said side bands to a load impedance, said wave filter being so arranged as to present substantially zero impedance to waves of the frequencies of said carrier wave and 10 said signal waves and to present to the selected wave modulation products a resistance substantially equal to the normal internal resistance of the modulating device.
2. A modulating system comprising in combination, a space discharge modulating device having an anode, a cathode, and a control electrode, means for impressing simultaneously upon said control electrode a carrier wave and a band of signal waves, 15 whereby there are generated in the space path of said device side bands of waves having frequencies differing from the carrier wave frequency by the frequencies of the signal waves, and a broad band wave filter 20 connected to said anode and said cathode adapted to transmit selectively one of said side bands to a load impedance, said wave filter being terminated at the junction with said device by a shunt impedance branch 25 comprising an inductance and capacity connected in parallel and resonant at substantially the frequency of said selected side bands.
3. In a wave transmission system, a source 30 of speech waves, a source of intermediate frequency carrier waves, means for modulating said carrier waves by said speech waves, means for selecting from the output of said modulation means a single intermediate frequency side band corresponding 35 to said speech waves, a source of high frequency carrier waves, a space discharge modulating device; means for impressing thereon to be modulated said high frequency and said selected intermediate frequency side band, whereby there are generated in said device 40 side band waves of the summation and of the difference frequencies of said impressed waves, and an output circuit connected to said modulating device including a broad-band wave filter, said filter being so arranged as to provide substantially short-circuit paths for waves of the impressed frequencies repeated by said space discharge modulator and to selectively transmit waves 45 of said difference frequency side band, the impedance thereto being substantially equal to that of said modulating device.
4. In a wave transmission system, a source of speech waves, a source of intermediate frequency carrier waves, means for modulating said carrier waves by said speech waves, means for selecting from the output of said modulation means a single intermediate frequency side band corresponding to said speech waves, a source of high frequency carrier waves, a space discharge modulating device, means for impressing thereon to be modulated said high frequency and said selected intermediate frequency side band, whereby there are generated in said device side band waves of the summation and of the difference frequencies of said impressed waves, and an output circuit connected to said modulating device including a broad-band wave filter, said filter being so arranged as to provide substantially short-circuit paths for waves of the impressed frequencies repeated by said space discharge modulator and to selectively transmit waves of said difference frequency side band, the impedance thereto being substantially equal to that of said modulating device.
5. In combination with a space discharge wave modulator an output circuit including a broad band wave filter, said filter being so arranged as to provide short circuit paths for waves repeated by said modulator and to transmit selectively wave modulation products of predetermined frequencies, offering thereto a resistance substantially equal to the internal resistance of the space discharge modulator.

In witness whereof, I hereunto subscribe my name this 13th day of January, A. D. 1925.

FRANKLIN MOHR.
